[57] CLAIM

The ornamental design for a combined bath and shower fixture unit, substantially as shown and described.

DESCRIPTION

FIG. 1 is a front perspective view of a combined bath and shower fixture unit showing my new design;

FIG. 2 is a side view thereof;

FIG. 3 is a rear view thereof;

FIG. 4 is a bottom plan view thereof.

The broken line representation of a portion of a bathroom wall in FIGS. 1 through 4 is for purposes of illustration only.

Fig. 3.

Fig. 4.

UNITED STATES PATENT AND TRADEMARK OFFICE
